COMBINATION ADJUSTABLE MOP AND BRUSH HOLDER

Filed Jan. 19, 1928

Frank N. Gilbert
Inventor

UNITED STATES PATENT OFFICE

FRANK N. GILBERT, OF BINGHAMTON, NEW YORK

COMBINATION ADJUSTABLE MOP AND BRUSH HOLDER

Application filed January 19, 1928. Serial No. 247,987.

This invention relates to improvements in combination mop and brush holders adapted for washing, brushing, waxing, and cleaning base boards and floors.

5 An object of the invention is the provision of an implement of the above character consisting of a head adapted to be held in a substantially vertical position by means of a handle during use and provided with clamping means capable, when not employed for holding a mop, of being used for supporting a brush or like cleaning implement in such position that it may be conveniently and advantageously used.

15 Another object of the invention is to provide an implement of this character in which the head is extensible vertically to accommodate at its side edges, mops, brushes, or the like, of varying lengths.

20 With the foregoing objects outlined and with other objects in view which will appear as the description proceeds, the invention consists in the novel features hereinafter described in detail, illustrated in the accompanying drawings, and more particularly pointed out in the appended claims.

In the accompanying drawings wherein an approved embodiment of the invention is illustrated

30 Fig. 1 is a rear elevation of the device;

Fig. 2 is an edge elevation thereof;

Fig. 3 is a front elevation of a modification;

Fig. 4 is a top plan view of such modification;

Fig. 5 is a perspective view of a brush constructed in accordance with the invention removed from the head or holder.

In this combination device, A (Figs. 1 and 2) designates the mop head which is preferably formed of a metal sheet having its side edges bent to form jaws 2, 2. These jaws 2, 2 cooperate with the yielding jaws 3, 3 which are hinged to the plate as indicated at 4 in the modification (Figs. 3 and 4). When used as a mop, suitable mop material (not shown) may be placed between the jaws and be held by the latter, and each yielding jaw is provided with tongues or handles 5, 5 (as in the modification), hav-

ing frictional contact with flat springs Y, shown in Figs. 3 and 4, to be used by the operator in manipulating the mop jaws 3, 3 cooperating with jaws 2, 2. The lower edge of the mop head is provided with the rollers 6, 6 to carry the mop head as it is used over the floor by the operator. A handle bracket 7 of sheet metal is attached to the rear face of the mop head by any suitable means, and carries a pivotally mounted handle socket 8, to which the mop handle 9 is connected. The handle 9 may be adjusted laterally on the bracket 7 and may be fixed in its adjusted position by means of a pin (not shown), which engages one or the other of the holes 11 in the bracket 7.

In the modified form of my device, the mop head is formed of two adjacent metal sheets a, a', one sheet a' having its edges bent to form jaws 2a, 2a, that cooperate with the yielding jaws 3a, 3a, which are also connected to the same plate a' by the hinges 4; and when used as a mop, suitable mop material may be placed between the jaws and held by the latter, as before described. The adjacent plate a, has connected to its lower edge, the rollers 6a, to carry this united mop head as it is used over the floor by the operator, the rollers forming the rotary support for the combined vertical mop head. The front plate a' bearing the springs Y, Y, and jaws 3a, 3a and 2a, 2a, has within it, a vertical slot 17, to receive a bolt having a thumb nut 16, the head of the bolt being secured to the front plate a. In this manner, when it is desired to adjust vertically the position of the plate a' and said jaws 2a, 2a, and 3a, 3a, in relation to plate a, and to the height of the vertical base board surface, it is accomplished by loosening the thumb nut 16 and the front plate a', with the jaws mounted thereon, can be raised, and by tightening the thumb nut 16, the jaws 2a, 2a, and 3a, 3a are held in a raised adjusted position, and in this manner, when used as a wiper for base boards or wall surface, the wiping pressure and surface contact may be adjusted as to height.

As a further part of my combined invention when used as a scrubbing or waxing device, I have the rectangular brush holder

having the top D, and vertical sides 12, projecting downward from the top D, the lower edge of sides 12 are turned inward, forming the turned in flanges 13.

5 As a further part of the device, I have mounted on said brush holder, the vertical projecting arms 14, 14, spaced apart and so positioned as to enter the opening formed between the jaws of the mop head, and with this sliding grip the head and brush holder may be moved toward one another until the roller 6, 6 rest upon the top D of the brush holder, and there removably held, as shown in Figs. 1, 2 and 3. On the outer edge of 10 the brush holder D, I have one or more screw pins 15, adjusted to enter or engage the head of the brush E as shown in the drawings, which brush E has slidable contact with brush head D, and so mounted and positioned, the combination device is adapted to be moved along the floor or other horizontal 15 surface by means of the handle 9, the jaws grasping the vertical arms 14, upon the brush holder, and moving the brush in contact with in the floor surface. When not in use for 20 brushing purposes, the jaws may be opened and the brush holder released from the mop head, and mop material inserted in the jaws, and the device used for mopping as before. 25

30 From the foregoing it is thought that the construction, operation, and advantages of the invention may be readily understood, and I am aware that changes may be made in the details disclosed, without departing 35 from the spirit of the invention, as expressed in the claims.

Having thus described my invention what I claim as new and for which I desire Letters Patent is as follows:

40 1. A brush comprising a flat head adapted to assume a vertical position, clamping jaws at each vertical edge of the head, a brush holder disposed beneath the head and on which the head rests, means carried by the 45 brush holder detachably engaging with the clamping jaws, and a brush carried by the brush holder.

2. A device of the character described comprising a head vertically positioned and having a hinged cooperating jaw formation on each vertical outer edge thereof, and a brush holder having spaced arms projecting upwardly from the brush holder for detachable engagement with the jaws.

50 3. A device of the character described comprising a head composed of two parallel adjacent adjustable plates, one slotted and slidable relative to the other and having a stationary and a hinged spring operated jaw 55 formation on each vertical edge thereof, guiding and clamping means mounted in the adjacent plate and passing through the slot in the first plate for controlling the vertical movement of said adjacent plate, a brush holder adapted to receive a brush, spaced

arms projecting from the brush holder and removably supported within the jaws of the slotted plate and a handle mounted on the head.

4. A device of the character described comprising a holding body having oppositely disposed jaws, a brush holder, spaced apart vertically disposed arms on the top thereof adapted for engagement with said jaws and means for adjustably holding a brush body 75 horizontally in the brush holding member.

5. A device of the character described, comprising a substantially vertical head plate having a handle attached thereto, a jaw formed on each vertical edge of said plate, movable jaws cooperating with the jaws formed on the plate, a brush holder having vertically projecting arms clamped between the jaws of the head.

In testimony whereof I have affixed my 85 signature.

FRANK N. GILBERT.
